UNITED STATES PATENT OFFICE

HOWARD G. BARTLING, OF CHICAGO, ILLINOIS, ASSIGNOR TO SEWALL PAINT & VARNISH COMPANY, OF KANSAS CITY, MISSOURI, A CORPORATION OF MISSOURI

RUBBING MACHINE

Application filed December 16, 1925. Serial No. 75,752.

This invention relates to improvements in rubbing machine for rubbing polished and varnished surfaces and also the surfaces of automobiles, and one of the objects of the 5 invention is to simplify the construction of such a rubbing machine and thereby materially reduce the cost of manufacture and at the same time increase the efficiency of the machine.

10 A further object is to provide an improved machine of this character embodying an extended or elongated rotatable rubbing element, the rubbing element being constructed of flexible rubbing material such as felt or 15 the like formed to produce spaced spirally arranged surfaces extending in general directions lengthwise of the rubbing element, being originally produced preferably as a solid cylindrical mass of material, the rubbing surfaces being then produced by cutting or forming grooves opening through the periphery of the element and extending spirally thereabout and in directions lengthwise of the element.

20 25 A further object is to provide improved means for securing the rubbing element to the driving shaft.

To the attainment of these ends and the accomplishment of other new and useful 30 objects the invention consists in the features of novelty in substantially the construction, combination and arrangement of the several parts hereinafter more fully described and claimed and as shown in the accompanying 35 drawing, in which

Figure 1 is a view in side elevation of a device of this character constructed in accordance with the principles of this invention.

Figure 2 is a sectional view taken on line 40 2-2, Figure 1.

Figure 3 is an isometric view of one of the rubbing elements before the spirally arranged rubbing surfaces are formed.

45 Figure 4 is a detail horizontal sectional view as taken on line 4-4, Figure 2.

Figure 5 is a detail perspective view of one of the fastening elements for securing the rubbing member or element to its driving shaft.

Figure 6 is a side elevation of one of the rubbing members.

Referring more particularly to the drawing the numeral 10 designates generally a 55 supporting structure which may be of any desired size and configuration and mounted thereupon is a motor or driving mechanism 11, a portion 12 of the structure being shaped to form a shield and a handle 13 is also provided by means of which the device may be 60 manipulated and transported.

Journaled in suitable bearings 14 and disposed beneath the shield 12 are a pair of 65 shafts 15 which are preferably substantially parallel and tubular and these shafts are driven through the medium of suitable driving mechanism (not shown) so that they will rotate in opposition to each other.

Mounted upon and secured to each of the 70 shafts 15 is a rubbing member, and as the construction of each of these members and the method of securing them to their respective shafts is the same, the description of one will apply equally as well to both.

Each of the rubbing members is preferably 75 of sectional construction, here shown as embodying two sections or elements 15^a, although it is to be understood any desired number of sections may be employed according to the size of the machine and the length 80 of rubbing members that it is desired to produce.

Each of the elements 15^a is originally preferably produced as a solid or homogeneous mass of flexible rubbing material such as felt 85 or the like and is provided with an opening 16 of any desired diameter extending longitudinally therethrough and through the ends thereof.

The periphery of the element 15^a is shaped 90 in any suitable manner to form spirally arranged and spaced substantially parallel rubbing portions 17 which are integral with the element and extend in general directions lengthwise of the element and form continuous work engaging portions, the spirals on one section of the element being arranged in opposite direction to the spirals on the adjacent section. The work engaging portions are preferably formed by cutting away the 95 100

material forming the element, for any desired depth, to form the spirally arranged grooves 18 between the surfaces 17 and the grooves are of a depth to allow a substantial amount of the body of the element to form a hub 19 at the center thereof and through which hub portion the opening 16 passes.

The shaft 15 is preferably tubular and is of a length substantially equal to the combined length of two of the elements 15^a arranged end to end. The shaft is provided with a longitudinal groove 20 extending lengthwise thereof and opening through the periphery and also through the free end of the shaft.

Screw threads 21 are provided at the inner end of the shaft upon which a nut or collar 22 is threaded.

20 The elements 15^a are sleeved upon the shaft 15 and are secured thereto for rotation therewith in any suitable manner but preferably as follows.

An annular member or washer 23 is provided with an inwardly projecting lug 24 and laterally projecting pins 25 which are preferably pointed, any number of which pins may be provided and they may be of any suitable length, but are of a length to 25 penetrate the adjacent end of the element 15^a for a considerable distance. The member 23 is first sleeved upon the shaft 15 until it abuts the nut or collar 22 and with the projection 24 entering the groove 20 in the shaft.

35 One of the elements 15^a is then sleeved upon the shaft and the pins 25 forced into the end of the element until the element abuts the member 23.

A similar annular element 26 is next 40 sleeved upon the shaft and is provided with a projection 27 which enters the groove 20 in the shaft. The element 26 is provided with laterally projecting impalement pins 28 on one side thereof adapted to enter the other 45 end of the element 15^a until the member 27 abuts the end of the element. Another element 15^a is sleeved upon the shaft so that the pins 29 will impale the end of the element and said end will then abut the member 27.

50 An annular member 30 having impalement pins 31 projecting from one face thereof is then sleeved upon the shaft 15 so that the pins will impale the adjacent end of the element 15^a, the member 30 may also be provided with a projection 32 adapted to enter the groove 20 in the shaft 15.

With this improved construction it will be manifest that the elements 15^a will be secured to the shaft 15 for rotation therewith.

60 Obviously the elements 15^a and the members 23-27 and 30 may be secured together before being placed upon the shaft 15 and they may then be placed upon the shaft as a unit instead of being built up upon the shaft.

65 The member 30 is preferably provided with

a laterally projecting collar or hub portion 33 which extends beyond the adjacent extremity of the shaft 15 to be engaged by the head 34 of a screw 35 that is threaded into the end of the shaft 15.

The screw 35 serves as a means for forcing the parts of the rubbing member together and for maintaining them against longitudinal displacement upon the shaft. By removing the screw 35 the entire rubbing member 70 may be readily removed from the shaft.

A disc like rubbing element 36 of suitable rubbing material such as felt or the like is provided with a central aperture to receive the hub like portion 33 of the member 30 and the head 34 of the screw 35 contacts with the face of the element 36 and secures the same to the end of the shaft 15. This element 36 is of a diameter substantially equal to the diameter of the rubbing members and is provided for the purpose of rubbing surfaces or corners which it is impossible to reach with the body of the rubbing member.

To the free end of the other of the shafts 15 is secured in any suitable manner a conically shaped or pointed rubbing element 37 and is constructed of any suitable material and is provided for the same purpose as the element 36.

The elements 15^a of each of the rubbing members on each of the shafts 15 are arranged so that the spirally arranged rubbing surfaces 17 and grooves 18 will extend about the respective rubbing members in opposite directions with respect to each other and the spirally arranged rubbing surfaces 17 and grooves 18 of the respective adjacent rubbing elements of the rubbing member will be also arranged to extend about the respective members in opposite directions with respect to each other.

With this arrangement it will be manifest that the rubbing or polishing composition or material that is placed upon the surface to be polished will not only be fed in a direction from the ends of the rubbing members towards the longitudinal center of the respective members, but as the rubbing members rotate in opposition to each other the spirally arranged grooves and rubbing surfaces will feed the rubbing compound towards the center of the machine.

The spirally arranged surfaces 17 will clean an uninterrupted or continuous surface to be presented to the work with the result that the formation of streaks or ridges on the polished surface will be obviated.

By the provision of the rubbing element 36 on the end of one of the shafts 15 and the rubbing element 37 on the end of the other 125 shaft 15, for rubbing in corners and between parts that cannot be reached by the main rubbing elements, there is provided a rubbing machine which will be of universal use.

By producing the sections of the rubbing members of a solid or single piece of material and then forming the spirally disposed rubbing surfaces, the cost of manufacture and of assembling the parts will be greatly reduced.

Obviously the grooves 18 and spirally arranged work engaging surfaces 17 may be formed in the rubbing element or section in any other manner than that described herein such as by molding. This construction also results in maintaining a uniform diameter of the rubbing members.

The shield 12 will prevent the rubbing material from being thrown away from the machine or upon the operator.

While the preferred form of the invention has been herein shown and described, it is to be understood that various changes may be made in the details of construction and in the combination and arrangement of the several parts, within the scope of the claims, without departing from the spirit of this invention.

What is claimed as new is:—

1. A rubbing machine including an elongated rotatable rubbing element formed of a single piece of flexible textile material having grooves opening through the periphery thereof to form a body portion having spaced flexible work engaging surfaces integral therewith and extending in general directions lengthwise of said element, said surfaces being comparatively wide with relation to their thickness.

2. A rubbing machine including an elongated rotatable rubbing element formed of flexible textile material, and a plurality of grooves opening through the periphery of the element and terminating short of the axis of the element to form a body with spaced and flexible work engaging portions integral therewith, said portions being comparatively wide with relation to their thickness.

3. A rubbing machine including an elongated rotatable rubbing element formed of flexible textile material, and a plurality of spirally arranged grooves opening through the periphery thereof and extending in general directions lengthwise of the element, said grooves terminating short of the axis of the element to form a body portion provided with spaced and continuous flexible work engaging portions integral therewith and comparatively wide with relation to their thickness.

4. A rubbing machine including a plurality of elongated rotatable rubbing elements, said elements being arranged end to end, and means mounting said elements for rotation in unison, each of said elements embodying a body portion and spaced spirally arranged flexible textile work engaging portions integral with the element, said portions being comparatively wide with relation to their

thickness, the spiral work engaging portions on the said elements being disposed in opposite directions.

5. A rubbing machine including a rotatable rubbing element, means for rotating said element, and a conically shaped flexible element secured to the free end of the first said element for rotation therewith, the base of the said conical element being disposed adjacent the said end of the first said element.

6. A rubbing machine including a shaft, a rubbing element sleeved upon the shaft, said element including flexible work engaging surfaces, an annular member sleeved upon the shaft, interengaging means between the said member and shaft for securing the member for rotation with the shaft, pins on the member and impaling the end of the rubbing element, an annular member sleeved upon the shaft adjacent the other end of said element, pins on the last said member and impaling the other end of the rubbing element, and a collar threaded upon the shaft and operating to force one of the said annular members towards the other.

7. A rubbing machine including a shaft, a rubbing element sleeved upon the shaft, said element including flexible work engaging surfaces, an annular member sleeved upon the shaft, interengaging means between the said member and shaft for securing the member for rotation with the shaft, pins on the member and impaling the end of the rubbing element, an annular member sleeved upon the shaft adjacent the other end of said element, pins on the last said member and impaling the other end of the rubbing element, and a collar threaded upon the shaft adjacent each of the said annular members and operable to force the said annular members in directions towards each other.

8. A rubbing machine including a shaft, a rubbing member embodying a plurality of rubbing elements sleeved thereon and arranged end to end, an annular member interposed between adjacent ends of the elements, pins projecting from both faces of said member and impaling the adjacent end of said elements, annular members on the shaft adjacent the free ends of said elements, pins projecting from the last said members and impaling the respective adjacent ends of the said elements, means causing said annular members to rotate with the shaft, an abutment adjacent the annular member at one end of the rubbing member, and a collar adjustably connected with the shaft adjacent the other end of the rubbing member and operable to force the annular members in directions towards each other.

In testimony whereof I have signed my name to this specification, on this 14th day of December, A. D. 1925.

HOWARD G. BARTLING.
